United States Patent Office.

P. CAVALIER, OF PLAINVIEW, MINNESOTA.

Letters Patent No. 71,454, dated November 26, 1867.

IMPROVEMENT IN ADJUSTABLE SCAFFOLD.

The Schedule referred to in these Letters Patent and making part of the same.

TO ALL WHOM IT MAY CONCERN:

Be it known that I, P. CAVALIER, of Plainview, in the county of Wabashaw, and in the State of Minnesota, have invented certain new and useful Improvements in Adjustable Scaffolds; and do hereby declare that the following is a full, clear, and exact description thereof, reference being had to the accompanying drawings, and to the letters of reference marked thereon.

In the annexed drawings, making part of this specification, A A represent a series of bars which are vertical, and B B represent a series of inclined bars, the two series being placed at a suitable distance apart, and framed together substantially as represented, so as to form a scaffold for builders' or painters' use. D represents the platform upon which the painter or builder stands. This platform is provided with a block and tackle at each end, by means of which it is suspended and adjusted. C C and C' represent the cross-pieces which connect the bars A and B at their upper ends. Upon these cross-pieces are small frames in which are hung the pulleys J J and K. The cords G and H, after passing from the blocks and tackle F F, being a continuation of said tackle, pass through or over the pulleys J J and K, and thence down through the centre of the scaffold-frame, and are provided at their lower ends with a suitable weight, I. The operator, by standing upon the centre of the platform, can, by means of the cords G and H, draw up or lower said platform at will. E E represent a series of rods which pass through holes made to receive them in the bars A and B, and support the platform while the operator is at work upon it. When the platform is drawn up to its highest point, it becomes fast between the uprights A and B, and by making the cords C and H fast, the operator can work upon said platform without changing the pins E E so as to hold it up.

Having thus fully described my invention, what I claim as new, and desire to secure by Letters Patent, is—

The arrangement of the scaffold-frame, constructed as specified, with the platform D, block and tackle F F, pulleys J J and K, and pins E E, substantially as and for the purpose herein set forth.

In testimony that I claim the foregoing, I have hereunto set my hand, this 12th day of August, 1867.

P. CAVALIER.
